FURNITURE

Louis E. Himelreich, Louisville, Ky., assignor to
 H. J. Scheirich Co., Louisville, Ky., a corporation
 of Kentucky

Application June 26, 1947; Serial No. 757,267

5 Claims. (Cl. 312—203)

1

This invention relates to articles of furniture having an extensible table or shelf, and in particular relates to kitchen cabinets.

Kitchen cabinets ordinarily are constructed of a base portion, the top of which provides a work table, and an upper section of lesser depth than the base, which is utilized for storage of various supplies or tools. As such bases are ordinarily constructed, it is not possible for the housewife seated at work in front of the cabinet to easily reach the supplies or tools lying on the work table. It has been proposed to overcome this difficulty by providing the cabinet base with an extensible top. However, such tops as heretofore constructed are unstably supported in the extended or retracted positions, and in extended position has an objectional inclination which causes round objects placed thereon to roll off.

Accordingly, it is an object of the present invention to provide a desk, table, cabinet or the like article of furniture having an extensible shelf, which is not objectionally inclined in extended position.

Another object is the provision of an extensible shelf or the like which is firmly supported in extended or retracted positions.

Another object is the provision of an improved cabinet structure having a base with an extensible shelf or top thereon, and which is locked against retraction when in extended position.

Still another object is to provide an improved cabinet structure having a separable base and top portion between which is located an extensible top or shelf; the shelf supporting and guiding means serving to secure the top and bottom sections together.

These and other objects will be apparent from a consideration of the following description taken in connection with the accompanying drawings wherein I have illustrated a preferred embodiment of the invention by way of example; and wherein:

Figure 1 is a front elevation of a kitchen cabinet embodying the invention;

Figure 2 is a fragmentary section on an enlarged scale taken on line II—II of Figure 3;

Figure 3 is a side view of Figure 1 viewed from the left;

Figure 4 is a section on an enlarged scale taken on line IV—IV of Figure 1, the top section being removed and the top or shelf being fully retracted;

Figure 5 is a view similar to Figure 4 showing the shelf fully extended;

Figure 6 is a plan view of a detail on an enlarged scale;

Figure 7 is a bottom view of a detail, and

Figure 8 is a side view of Figure 7 as viewed from the right.

The drawing illustrates a kitchen cabinet by way of example, and it is to be understood that the invention is not limited thereto.

2

Referring to the drawings, the lower section 11 of the kitchen cabinet carries at its sides track members 12 and 13, which may be located adjacent the top as shown. As these track members are alike in construction, only one will be described in detail. The track member 12, in the preferred embodiment, is in the form of a channel member of metal or other suitable material, and has a horizontal flange 14, a vertical wall 15, and may, if desired, have a second horizontal upper flange 16 spaced from the flange 14. The lower flange 14 may have struck out portions to form perforate tabs 18 and 19, and the track member 12 is secured to the lower cabinet section 11 by screws or the like passing through said tabs, so that the lower flange 14 rests upon the top of the lower cabinet section. However, if desired, the top side edge of the cabinet base may be cut away so that the top surface of lower track or flange 14 lies flush with the top of the cabinet base. Or, if desired, a suitable slide button or plate 20 may be secured to the top of the front leg to compensate for the thickness of flange 14. The track member 13 is similarly secured to the opposite side of the cabinet base.

In the construction shown, the upper cabinet section 11a is located with its lower edge resting on the upper flanges 16 of the track members 12 and 13, and is secured in place by screws or the like passing through perforate tabs 21 and 22 similarly formed from the upper flange 16. The top of the cabinet section thus is removably secured to the base and can be readily disconnected for transportation as desired, and can be readily reassembled. The height of vertical wall 15 determines the space between the upper and lower sections of the cabinet, and a table top or shelf 17 rests upon the upper surfaces of flanges 14, the opposite edges thereof being embraced by the channel members 12 and 13. Adjacent each side of the shelf are guide members 23 and 24 which are suitably secured to the underside thereof, as by screws passing through holes therein, and alternate holes may be provided, if desired, to allow for lateral adjustment. Each guide member comprises preferably a plurality of offset fingers 25 and 26 which engage the undersides of flanges 14. Channel members 12, 13 preferably extend for less than the depth of the upper section 11a of the cabinet, and the fingers 25 and 26 preferably are spaced approximately the length of flanges 14, so that with the shelf 17 in normal retracted position both sets of fingers 25, 26 engage the undersides of the flanges 14. Fingers 25, 26 also preferably have vertically extending portions 27 which, as illustrated, engage the upper wall portion of the cabinet to prevent or limit cocking of the shelf in its sliding movement.

Adjacent the forward part of the cabinet base are located dowels 28, and the underside of for-

ward fingers 26 preferably are sloping so that they may ride forwardly over the dowels 28 and the fingers are received between the dowels and the front portion 29 of the cabinet base when the shelf is lowered. In this position the shelf 17 bears at the front on the top of front portion 29 of the cabinet base and its rear lies over the flanges 14, the rear fingers 25 acting to prevent raising of the rear of the shelf when a downward pressure is applied to the extended forward portion of the shelf. Also in this position the dowels 28 engage the rear edge of the forward fingers 26 to prevent the shelf being retracted, while the front fingers 26 engaging leg 29 of the cabinet base prevent the shelf from being entirely pulled out by a direct pull.

In retracted position of the shelf as shown in Figure 4, the shelf lies upon the flanges 14 in horizontal position with the rear fingers 25 engaging the underside of the flanges to prevent tilting of the shelf. To extend the shelf, it is drawn forwardly, and when forward fingers 26 reach the dowels 28 they ride thereover until the fingers drop into position between the dowel pins 28 and the front portion 29 of the cabinet base, thus allowing the shelf to be supported at the front end by the cabinet base while the rear of the shelf rests on the flanges 14 and the rear fingers 25 engage under the flanges 14 to prevent tilting of the shelf when a downward pressure is applied to the front of the shelf. In this position the shelf is stable and will not rock regardless of how the load on the shelf may be shifted. The space between flanges 14 and 16 allows the shelf to be retracted between the upper and lower cabinet sections, which are secured together by the channel members 12 and 13 so as to form a single unit.

The shelf may be removed by raising it to the dotted line position shown in Figure 5 in which position the front finger 26 clears the top of the front leg of the cabinet so that the shelf can be entirely withdrawn if desired. The shelf is assembled by placing it in the dotted line position so that the front fingers clear the top of the front leg, and then it may be pushed back to operative position.

The invention may be embodied in other specific forms without departure from the spirit or essential characteristics of the present invention. The specific form described herein therefore is to be considered in all respects as illustrative and not restrictive of the invention.

What I claim as my invention and desire to secure by United States Letters Patent is:

1. An article of furniture comprising an open top base portion having channel members on the top thereof of lesser length than the depth of the base portion and providing inturned flanges, a shelf of greater length than the depth of the base portion slideably bearing on said flanges at the edges thereof and loosely embraced by said channel member to limit upward tilting thereof, guide means on the bottom of said shelf comprising rear and forward fingers located to engage the bottom surfaces of said flanges adjacent the ends thereof when the shelf is in retracted position, the forward edge of the base portion providing a support for said shelf, and means adjacent said forward edge of said base located in the path of movement of said fingers whereby said shelf must be lifted in moving to extended position to clear said means, said means engaging behind said forward fingers when said shelf is

lowered in extended position to retain said shelf against retractile movement.

2. An open top article of furniture comprising a base portion having channel members secured to the sides thereof adjacent the top and providing inturned flanges on the top of the base portion of lesser length than the depth of the base portion, a top cabinet portion of lesser depth than the base portion secured in spaced relation to the base portion, a top for the base portion comprising a shelf having its lateral edges slideably embraced by said channel members and resting on said flanges and base top, guide means on the bottom of said shelf comprising spaced front and rear fingers located to engage the bottom surfaces of said inturned flanges when the shelf is in retracted position, said fingers being spaced the length of the channel members, pins adjacent the front end of said base located to engage said front fingers when the shelf is extended, in which position the front fingers disengage the flanges to allow tilting of the front end to enable the front fingers to ride over said pins, said front fingers serving as stops engaging the front of the base to prevent removal of the shelf by a direct pull, and said pins engaging behind said front fingers when said shelf is in extended position to prevent retractile movement thereof.

3. An article as specified in claim 2 wherein said channel members have perforate tabs struck out and extending vertically for securing said channel members to said base and top portion.

4. An article as specified in claim 2 wherein said front fingers have inclined lower surfaces to facilitate riding over said pins in moving the shelf to extended position.

5. An article of furniture comprising: a base portion having opposed guides, a shelf having its opposite edges slideably bearing on said guides, pairs of spaced rear and front fingers located at each side of the shelf to engage the bottom surfaces respectively of said guides adjacent the ends of the guides when the shelf is in retracted position, means adjacent the forward edge of said base projecting into the path of the movement of said front fingers, the fingers in each pair being so spaced that when said front fingers engage said projecting means they have become disengaged from said guides to allow upward tilting of the front end of the shelf in moving to extended position to allow the front fingers to clear said projecting means, said projecting means engaging behind said front fingers when the shelf is lowered in extended position to retain said shelf against retractile movement, and stop means to limit extended movement of the shelf to maintain the rear fingers in engagement with said guides.
